JAMES L. JOHNSON AND J. WILSON FOUST, OF EVANSBURG,
PENNSYLVANIA.

Letters Patent No. 83,970, dated November 10, 1868.

IMPROVEMENT IN HAND-SPINNING MACHINE.

The Schedule referred to in these Letters Patent and making part of the same.

To all whom it may concern:

Be it known that we, JAMES L. JOHNSON and J. WILSON FOUST, of Evansburg, in the county of Crawford, and State of Pennsylvania, have invented a new and useful Improvement in Spinning-Frames; and we do hereby declare that the following is a full, clear, and exact description thereof, which will enable those skilled in the art to make and use the same, reference being had to the accompanying drawings, forming part of this specification.

Our invention relates to improvements in spinning-frames, the object of which is to provide a simple and effective apparatus for the purpose.

It consists in an arrangement of apparatus for preserving the proper tension on the driving-belt, as will be hereinafter more fully described, reference being had to the accompanying drawings, wherein is shown a side elevation of a spinning-frame, with our improvement applied, the front rail being removed.

A represents the frame of the machine;

B, the driving-wheel, which communicates motion to the multiplying-wheel C, supported in a swinging frame, having its axis at C.

E represents a belt working over the pulleys C and D, and communicating motion to the spindle F, which is supported in posts rising up from the carriage G.

H represents a contracting and expanding-frame, com-

posed of two series of toggle-arms, joined together by toggle-joints, the two series being pivoted together, and operated by a swinging lever, I, which derives its motion from a foot-treadle, K, arranged upon a platform suspended from the frame of the machine.

The support of the pulley D is connected adjustably to the frame, whereby it may be moved to tighten the belt E.

The support of the pulley C is also arranged upon an axis, and provided with a ratchet-wheel, a, and pawl b, for the same purpose.

The said frame H is connected at one end to the frame of the machine, and at the other to the spindle-carriage, and, being operated by the treadle, as aforesaid, thereby communicates to the spindle-frame G the necessary reciprocating motion.

We claim as new, and desire to secure by Letters Patent—

The combination of pulley C, having a vibrating support, the ratchet a, pawl b, and the pulley D, having an adjustable support, all constructed, arranged, and operating substantially as and for the purpose described.

JAMES L. JOHNSON.
J. WILSON FOUST.
